CLAIM

The ornamental design for a tubular food container, as shown and described.

DESCRIPTION

FIG. 1 is a side elevational view of a tubular food container showing my new design;

FIG. 2 is a side elevational view of a second embodiment of the tubular food container;

FIG. 3 is a top plan view of FIG. 1;

FIG. 4 is a bottom plan view of FIG. 1;

FIG. 5 is a perspective view of FIG. 1;

FIG. 6 is a perspective view of FIG. 2;

FIG. 7 is a side elevational view of a third embodiment of the tubular food container;

FIG. 8 is a side elevational view of a fourth embodiment of the tubular food container;

FIG. 9 is a perspective view of FIG. 7;

FIG. 10 is perspective view of FIG. 8;

FIG. 11 is a fragmentary cross-sectional view taken along line 11—11 of FIG. 1; and,

FIG. 12 is a fragmentary cross-sectional view taken along line 12—12 of FIG. 2.

The top and bottom of the third (FIG. 7) and fourth (FIG. 8) are the same as disclosed in FIGS. 3 and 4 of the first embodiment (FIG. 1).
